Primary Examiner — Melody Brown(74) *Attorney, Agent, or Firm* — Christensen O'Connor Johnson Kindness PLLC(57) **CLAIM**

The ornamental design for a vehicle bumper unit, as shown and described.

DESCRIPTION

FIG. 1 is a top perspective view of a vehicle, bumper unit for a vehicle according to our new design;

FIG. 2 is bottom perspective of the vehicle bumper unit of FIG. 1;

FIG. 3 is a front view of the vehicle bumper unit of FIG. 1;

FIG. 4 is a top view of vehicle bumper unit of FIG. 1; and,

FIG. 5 is a bottom view of vehicle bumper unit of FIG. 1.

FIGS. 1-5 illustrate a first embodiment of our novel design suitable for use on the left side of a vehicle. Our novel design also includes a second embodiment suitable for use on the right side of a vehicle, which is mirror symmetrical to FIGS. 1-5 and therefore not separately illustrated.

The rear of the vehicle bumper unit is unornamented.

The broken lines immediately adjacent the shaded areas as depicted in the FIGURES, represent the bounds of the claimed design while all other broken lines are directed to environment and are for illustrative purposes only; the broken lines form no part of the claimed design.
